Attorney

UNITED STATES PATENT OFFICE.

MARTHE FAURE, OF TULSA, OKLAHOMA.

HAIR-CURLING DEVICE.

Application filed August 21, 1925. Serial No. 51,591.

My present invention relates to a device for curling hair and its principal object is the provision of simple and inexpensive means, as above, which will produce curls or undulations in the hair in two planes.

Another object of the invention is the provision of means in the curling device whereby an adjustment may be made to tighten the hair against the projections of the curling device.

Still another important object is the provision of such a device which will not injure the hair and which may be readily inserted within any desired form of tubular electric heater, to which no claim is made, and which is common practice. The hair after being properly twisted on the device, may be wrapped with a fabric containing moisture or other lotion, before insertion in the heating element, so that the hair may be treated and curled in the same operation.

To this end my invention includes a device having projections at approximately right angles to each other and in staggered relation, the hair being adapted to be twisted around the projections, first on one side and then on the other of the device. In between the projections I provide a movable element adjustable by set screws from the rear, which may be made to move outward from the device so that it will be possible to tighten the hair being curled on the device, as may be desired.

I have illustrated in the accompanying drawing, the preferred form of apparatus for carrying out the above operation, but it is understood that this is merely diagrammatic and illustrative of one embodiment of the invention, as obviously it may be carried out in various ways and with divers mechanisms.

In these drawings:—

Figure 1 is a plan view of one form of my invention, showing the same in use.

Fig. 2 is a side elevation of the device of Fig. 1.

Fig. 3 is a sectional elevation on the line 3—3 of Fig. 2.

Fig. 4 is a longitudinal sectional view on the line 4—4 of Fig. 3.

Referring now with particularity to the form illustrated, I have shown a base block 1, composed of any desired material and which will not corrode or injure the hair,

and outstanding therefrom, at approximately right angles to each other, projections 2 and in staggered relation to each other. These projections 2 are provided with an over-hanging ledge 3 at the top thereof, the entire projection being segmented.

Between the projections 2 on each side of the base 1, I provide a movable adjusting element 4 fitted in a trough or socket 5 longitudinally of the base and engaged on its bottom by set screws 6 penetrating the base, the heads of said set screws being accessible from the bottom of the base 1. It will be apparent that after the hair has been twisted as desired on the projections, the same may be made loose or tight on said projections by taking up or letting off of the set screws 6.

In order to securely retain the hair in proper position, I provide at one end of the base 1, a depression 7 which is adapted to take the large end of the strand of hair, which is then secured in position by means of a swivel hook 8 engaging a screw 9, or a like device. Before the strand of hair is passed around the first projection, it is made to pass from the depression 7 around a curved stud 10 as clearly illustrated.

At the opposite end of the device, I provide an end stud 11 having an over-hanging top 12, which is adapted to receive the end of the strand of hair being curled, which may be twisted about said end stud as in a half hitch, which will hold the same securely in place.

When the hair has thus been secured in the device, it may then be wrapped in a cloth wet with water or any desired lotion for the treatment of the hair, and inserted within an ordinary tubular heating device so that the hair may be treated while being subjected to heat.

It is to be understood that all parts of the device with which the hair is to come in contact, will have their corners smoothed off and every effort will be made to produce even undulations in the hair, by having the hair engage a curved surface rather than an angular one.

It will be readily observed that the hair once intertwined back and forth between the projections, made tight and heated, will assume a curl longitudinally and laterally,

which gives a very pleasing marcel effect without injurious effects upon the hair, and in a very inexpensive manner.

Having thus described my invention, what

5 I claim is:—

1. A hair curling device including a base element of substantially triangular cross section having projections on two of its faces, means to tighten hair intertwined between the projections on opposite faces, said hair tightening means comprising a bar arranged longitudinally of the base and between the projections.
- 10 2. A hair curling device including a base element of substantially triangular cross section having projections on two of its faces, means to tighten hair intertwined between the projections on opposite faces, said hair tightening means including a bar ar-

ranged between opposite projections and 20 adapted to underlie the hair, and means for moving the bar in relation to the base.

3. A hair curling device including a base element of substantially triangular cross section having projections on two of its 25 faces, means to tighten hair intertwined between the projections on opposite faces, said hair tightening means including a bar arranged longitudinally of the base and between opposite projections and lying in a 30 socket in the base, and a set screw passing through the base and engaging the bottom of the bar, movement of said screw causing movement of the bar outwardly from the base. 35

In testimony whereof I affix my signature.

MARTHE FAURE.
